UNITED STATES PATENT OFFICE.

HUGH WALLACE, OF DAYTON, OHIO, ASSIGNOR TO GENERAL MOTORS RESEARCH CORPORATION, OF DAYTON, OHIO, A CORPORATION OF DELAWARE.

LIQUID PUMP.

Application filed August 28, 1925. Serial No. 53,148.

This invention relates to liquid pumps and particularly to liquid fuel pumps for internal combustion engines. One of the objects of the present invention is to improve the 5 construction of liquid pumps and reduce the cost of manufacture thereof. In order to accomplish this object the present invention comprises a frame which is adapted to be attached to the engine or other machines 10 which operate a pump, the frame providing a pulsating chamber and a liquid outlet. A pulsator driven by the engine reciprocates within the chamber and tends alternately to compress and rarefy the air therein thereby 15 causing fuel to flow from the pump inlet to the pulsating chamber and out through the outlet. The frame has a cover which provides a chamber inlet and a pump valve controlling passage from the inlet into the pulsating chamber. The outlet check valve of 20 the pulsating chamber is carried by the frame.

A further object of the invention is to control the liquid pump so that if pressure of 25 liquid at the outlet of the pump exceeds a certain amount no more liquid will be delivered from the supply tank to the pump. In the present invention this is accomplished by providing the frame with a chamber connected with the pump outlet, and by locating in the chamber a movable element responsive to variations in liquid pressure and by providing a valve actuated by the movable element for preventing flow from the 30 source of supply to the inlet check valve of the pump while at the same time opening another valve which connects the pump outlet with the pump inlet check valve so that any liquid in the pump chamber may 35 be circulated through the pulsating chamber.

Further objects and advantages of the present invention will be apparent from the following description, reference being had to the accompanying drawings wherein a 40 preferred form of embodiment of the present invention is clearly shown.

In the drawings:

Fig. 1 is an end elevation partly in section of an engine or another machine having 45 applied thereto a form of the present invention.

Fig. 2 is a sectional view on line 2—2 of Fig. 4.

Fig. 3 is a sectional view on line 3—3 of 50 Fig. 2.

Fig. 4 is a sectional view on line 4—4 of Fig. 7.

Fig. 5 is a sectional view on line 5—5 of Fig. 4.

Fig. 6 is a bottom view on line 6—6 of Fig. 4.

Fig. 7 is a side elevation in the direction of the arrow 7 of Fig. 4 and arrow 7 of Fig. 1.

Fig. 8 is a sectional view on the line 8—8 of Fig. 4.

A machine frame, designated by numeral 20 in Fig. 1, supports a driven shaft 21 carrying an eccentric 22 which cooperates with an eccentric strap 23 connected by an arm 24 with a pin 25 attached to a piston 26. The piston 26 is made tubular for sake of lightness and is closed at its upper end by plug 27. The parts 26 and 27 therefore constitute the reciprocating member of the pump which is guided by the cylindrical wall of a pulsating chamber 28 which is provided by the pump frame 29. The frame 29 is adapted to be secured to the machine frame 20 by screws 30. The chamber 28 is closed by the piston elements 26 and 27 and also by a gasket 31 and a cover plate 32 attached to the frame 29 by screws 32a. Cover 32 is provided with an arcuate groove 33 which provides an extension of the pulsating chamber 28 when the cover is in position. Cover 32 includes a tube 34 having its lower end threaded at 35 to receive a plug 36 for maintaining in position a cylindrical screen 37 which fits at its upper end over an annular boss 38. The side wall of the tube 34 is provided with a threaded opening 39 for receiving a pipe leading from a source of liquid supply. The annular boss 38 surrounds a passage 40 in alignment with a passage 41 of the same diameter in the frame 29. Passage 41 merges at a valve seat 42 into a smaller passage 41a, and passage 41a merges into a still smaller passage 43a extending through a valve seat 43. Referring 45 more particularly to Fig. 2, the passage 41a in the frame 29 is connected by a transverse passage 44 with a passage 45 which is parallel to the passage 41a. As shown in Fig. 3, passage 45 communicates with the passage 33 in the cover 32 through a valve seat member 46 carried by the cover 32. The passage in the valve seat 46 is normally closed by check valve 47 urged by spring 48 against the seat 46. The outlet of cham-

passage 41 of the same diameter in the frame 29. Passage 41 merges at a valve seat 42 into a smaller passage 41a, and passage 41a merges into a still smaller passage 43a extending through a valve seat 43. Referring 50 more particularly to Fig. 2, the passage 41a in the frame 29 is connected by a transverse passage 44 with a passage 45 which is parallel to the passage 41a. As shown in Fig. 3, passage 45 communicates with the passage 33 in the cover 32 through a valve seat member 46 carried by the cover 32. The passage in the valve seat 46 is normally closed by check valve 47 urged by spring 48 against the seat 46. The outlet of cham- 55

ber 33 is through a ported valve seat 49 which is normally closed by a check valve 50 which is urged against the seat 49 by a spring 51. The check valve 50 is housed 5 within a valve cage 52 provided by the frame 29 and the cage 52 is connected by passage 53 with the fuel reservoir 54 which is provided by the frame 29, the reservoir 54 being closed by cover 55. Passages 56, 10 57 connect the reservoir 54 with a threaded opening 58 for receiving a liquid outlet pipe.

Within the reservoir 54 there is located a flexible metal bellows 60 having its upper end attached to the cover 55. The lower end of the bellows is attached to a valve stem 61 having a shank 62 which extends through the bottom wall of the bellows 60 and is riveted against a washer 63. The cover 55 carries a plug 64 having a tubular shank 20 65 which provides a stop limiting the upward movement of the washer 63, and which provides a guide for a spring 66 which is located between the head of the plug 64 and the bottom wall of the bellows 60. The plug 25 64 is provided with passages 67 and 68 which vent the interior of the bellows. By turning the plug 64 the initial compression of spring 66 can be adjusted for a purpose to be described. The valve stem 61 is provided with 30 valves 72 and 73 which cooperate respectively with the valve seats 42 and 43. The valve 72 is provided with a plurality of radially extending arms, one of which is shown at 74. These arms receive the upper end of a spring 75 the lower end of which is supported by an annular shelf 76 surrounding the passage 40. The spring 66 normally exerts greater force downwardly than the spring 75. 35 exerts upwardly so that normally the valve 73 will be moved against its seat 43 and the valve 72 will be separated from its seat 42.

The downward movement of the piston 26 will tend to rarefy the air in the pulsating chamber 28 thereby causing the check valve 45 50 to remain closed and the check valve 47 to open. Fuel will flow into the pulsating chamber 28 through inlet 39, tubular extension 34 of cover 32, screen 37, passage 40, passage 41, valve seat 42, passage 44, passage 45 and valve seat 46. The upward stroke of the piston 26 tends to compress the fluid in chamber 28 thereby causing the valve 50 to open and valve 47 to close. The liquid within the chambers 28 and 33 will be forced 55 through the passages 52 and 53 into the reservoir 54 and then out through liquid delivery passages 56, 57 and 58.

When the pressure of liquid in the reservoir 54 exceeds a certain amount the bellows 60 will be compressed upwardly sufficiently 60 to cause the valve 72 to engage its seat 42 and the valve 73 to be moved away from its seat 43. In this way the passage of liquid from the tube 34 into the passage 41^a will be 65 prevented, but the liquid may pass from the

reservoir 54 into the passage 41^a through the passage 43^a in the valve seat 43. Therefore after valve 72 closes and the valve 73 opens, fluid in the reservoir 54 will be recirculated by the operation of the pulsating member 26. 70

The pump is particularly adapted for supplying liquid fuel to the carburetors of internal combustion engines. The liquid level of the carburetor is controlled by a float controlled valve in the bowl of the carburetor. When this valve closes, further operation of the fuel pump will cease. The valve 72 will be closed so that no more fuel will be delivered to the pump until the carburetor float valve opens to permit more fuel to be delivered to the carburetor. The liquid pressure at which the valve 72 closes and valve 73 opens is controlled by turning the plug 64 so as to adjust the initial compression of the spring 66. 80 85

This pumping apparatus is particularly adapted to be attached to the crankcase of an internal combustion engine. The engaging walls of the piston 36 and chamber 28 are lubricated by the oil splashed in the 90 crankcase of the engine. It is apparent from the drawings illustrating the invention that the invention may be produced economically on account of its simple construction and may be readily installed upon an internal combustion engine or other machines with 95 which the pump may cooperate.

While the form of embodiment of the present invention as herein disclosed, constitutes a preferred form, it is to be understood that other forms might be adopted all coming within the scope of the claims which follow. 100

What is claimed is as follows:

1. A liquid pump comprising, in combination, a frame adapted to be attached to a machine which operates the pump and providing a pulsating chamber and a pump outlet, a reciprocating pulsator within the chamber, a valve carried by the frame and controlling communication between the pulsating chamber and the pump outlet, a cover for the frame providing a pump inlet connected with the pulsating chamber, and a pump valve controlling the passage from the inlet to the pulsating chamber. 110 115

2. A liquid pump comprising, in combination, a frame adapted to be attached to a machine which operates the pump and providing a pulsating chamber and a pump outlet, and a reservoir connected with the pump outlet, a reciprocating pulsator within the chamber, a valve carried by the frame and controlling the passage from the chamber to the reservoir, a cover for the frame providing a pump inlet connected with the pulsating chamber, a pump valve controlling the passage from the inlet to the pulsating chamber, and means responsive to pressure in the reservoir for closing communication between the pump inlet and inlet valve, and for open- 120 125 130

ing a passage between the reservoir and pump inlet valve.

3. A pump structure adapted to be mounted as a unit upon a machine frame and comprising, in combination, an inlet duct, an outlet duct, a reservoir connected with the outlet duct, a pulsating chamber and reciprocating pulsator therein, and pressure re-

sponsive means for interrupting fluid flow from the inlet duct to the chamber and for causing fluid to flow from the reservoir to the chamber. ¹⁰

In testimony whereof I hereto affix my signature.

HUGH WALLACE.
